(57) CLAIM

I claim the ornamental design for a wall mount face plate with arm, as shown and described.

DESCRIPTION

FIG. 1 is a perspective view of a wall mount face plate with arm showing the claimed design;

FIG. 2 is a side elevational view of FIG. 1;

FIG. 3 is a side elevational view of FIG. 1 opposite that of FIG. 2;

FIG. 4 is a front elevational view of FIG. 1;

FIG. 5 is a rear elevational view of FIG. 1;

FIG. 6 is a top plan view of FIG. 1; and,

FIG. 7 is a bottom plan view of FIG. 1.

The broken lines in the drawings represent unclaimed subject matter and form no part of the claim.
